UNITED STATES PATENT OFFICE

126,356

DESIGN FOR A PIE PLATE

George H. Brown, Highland Park, Ill.

Application March 9, 1940, Serial No. 90,791

Term of patent 14 years

To all whom it may concern:

Be it known that I, George H. Brown, a citizen of the United States, residing at Highland Park, in the county of Lake and State of Illinois, have invented a new, original, and ornamental Design for a Pie Plate, of which the following is a specification, reference being had to the accompanying drawing, forming a part thereof.

Fig. 1 is a top plan view of a pie plate, showing my new design, the design shown in the portion A to A' continuing around the pie plate as indicated by the dotted lines.

Fig. 2 is a transverse sectional view on the center line thereof.

Fig. 3 is a side elevational view thereof, the dot and dash lines indicating that the design is continuous around the pie plate.

I claim:

The ornamental design for a pie plate, as shown and described.

GEORGE H. BROWN.
